Patented Feb. 16, 1965

200,303

DOLLY

Robert D. Handley, Jackson, Mich., assignor to Handley Industries, Inc., Jackson, Mich., a corporation of Michigan

Filed Feb. 6, 1964, Ser. No. 78,550

Term of patent 14 years

(Cl. D14—3)

—FIG. 1

—FIG. 6

FIG. 1 is a front perspective view of a dolly showing my new design,

FIG. 2 is a top plan view,

FIG. 3 is a side elevational view, the opposite side being of similar appearance,

FIG. 4 is a bottom view,

FIG. 5 is a rear elevational view of a dolly of my design, and

FIG. 6 is a front elevational view.

I claim:

The ornamental design for a dolly, substantially as shown and described.
